CHIROPRACTIC MACHINE

Albert H. Binash, Oak Park, William A. Tull, Midlothian, and Roy T. Gautney, Chicago, Ill.

Application September 14, 1944, Serial No. 554,034

4 Claims. (Cl. 128—72)

1

The present invention relates to a device or machine used in chiropractic therapy or similar treatment, and has reference more particularly to that part of the means for affecting a more safe, even, and reactive stressing of the abdominal portion of a patient.

Among the objects of the invention is to provide a novel device in the type of a machine referred to for treating the abdomen of a patient by direct reactive stresses uniformly acting throughout the extent of the abdomen, the novel device having a resilient pad or cushion for protecting the abdomen of the patient as it is pressed against the abdomen and also resilient means such as springs and spring stressed parts, for pressing the pad against the abdomen, the springs being particularly designed to effect a straight or right line movement or motion at a normal or perpendicularly to the abdomen. The means for holding and pressing up against the pad is of the nature of a pantographic or lazy tong structure and has relatively long springs for stressing the lever or like elements of the device to eliminate or reduce to a minimum any attendant rebound action that usually is peculiar to stressed spring reactions, so as to protect the patient from shock or injury or a too quick recovery or restoring of the chiropractically stressed parts of the patient's body which is under treatment. Also, there is preferably additional relatively long springs acting directly against the abdominal pad so as to coordinate with the springs which react through the lever arrangement referred to above. Thus safety against bruising and injury to the ribs and thorax of the patient is attained, and ease and comfort of movement of the patient's body, especially the abdominal portion, as also the thorax is attained and enjoyed.

The invention also comprehends means for holding the pad in stationary position when a varied treatment of the patient is desired in which a movement of the abdomen is not necessary.

Other objects, advantages, capabilities, features, and the like are comprehended by the invention as will later appear and as are inherently possessed by the invention.

Referring to the drawings:

Fig. 1 is a side view in elevation with parts broken away of part of a machine embodying our invention;

Fig. 2 is a perspective view of the device;

Fig. 3 is a plan sectional view taken in a plane represented by line 3—3 in Fig. 1 of the drawings;

2

Fig. 4 is an end view in elevation, on a reduced scale, of the device;

Fig. 5 is a fragmentary part sectional view taken in a plane represented by line 5—5 in Fig. 5 11 of the drawings;

Fig. 6 is a fragmentary end view of the device;

Fig. 7 is a sectional view taken in a plane represented by line 7—7 in Fig. 6 of the drawings; and,

Fig. 8 is a side view showing the use of the 10 device.

Referring more in detail to the drawings the embodiment selected to illustrate the invention is shown in connection with a device to be used in chiropractic treatment and having longitudinally 15 extending supporting members 11, such as bars or tubes on which are suitably supported pads or the like 12 and 13, and between said pads is supported a pad or the like 14, on a mechanism later described and forming part of the present invention.

20 The latter mechanism comprises a lower base member 15 mounted upon the bars 11 and held in position against lateral movement relative to the bars 11 by strips 16 (see Fig. 4) fixed to the base piece 15 and located adjacent to the bars 11, and upper base member 17, which is parallel to the base member 15, and upon the base 17 is mounted the pad 14. The pad 14 is preferably provided with a cushion of resilient or flexible material 18, such as sponge rubber or the like, and a sheet covering 19. The cushion 18 and the covering 19 25 may be connected or secured to the base 17 in any suitable manner.

On the base 15 at an end thereof and near the sides thereof are secured bearing brackets 20 35 and 20 of the strap type and having base flanges 21 and 21 suitably secured to the base 15, as by suitable securing elements such as screws or bolts 22. Likewise to the under side of the upper base 17 at an end thereof and at the sides thereof are 40 secured like bearing brackets 23 and 23 of the strap type and having base flanges 24 and 24 suitably secured to the base 17, as by suitable securing elements such as screws or bolts 25. The brackets 23 are vertically above corresponding brackets 20. In each of these brackets 22 and 23 is firmly held a suitable bearing unit 26, which 45 may be of a roller or ball bearing type.

Extending laterally through the lower and upper bearing units 26 and 26 are shafts 27 and 28 which are suitably secured to the central rotor part of each bearing unit. The ends of these shafts 27 and 28 are suitably threaded to carry nuts 29 and 30 (see Fig. 3) so as to act as collars or abutting elements at each side of the bearing units 26 (see also Fig. 4).

To the outer projecting end parts of the shafts 27 and 28 are connected the ends of pantographic or lazy tong lever arms 31 and 32, at both sides of the device, and said ends are clamped against the nuts 29 by end nuts 33. Fixed to arms 31 and 32 and extending therewith are auxiliary lever arms 34 and 35 which act as lateral bracing arms. These arms have laterally extending foot parts 36 and 37 and toe parts 38 and 39 which are suitably apertured to receive the shafts 26 and 27 and which are held to the shafts 26 and 27 by suitable nuts 40 and 41. Where these lever arms 31-34 and 32-35 cross they are provided with suitable fulcrum apertures for receiving a cross shaft 42 which acts as the fulcrum shaft for the lever arms. On this shaft 42 are thrust washers 43 which are located between the lever couples 31-34 and 32-35, and on the outer sides of these lever couples are secured on the shaft 42 thrust nuts 44 and 45, of which the nuts 45 are on the ends of the shaft 42 (see Fig. 3 in particular).

The lower ends of lever arms 32 and the upper ends of lever arms 31 are apertured to receive the end portions of cross shafts 46 and 47 the latter having thrust nuts 48 and 49 on the ends of the shafts 46 and 47, and the lower end parts of the arms 35 and the upper end portions of the arms 36 have foot parts 50 and 51 and toe parts 52 and 53, and these toe parts have suitable apertures for receiving the cross shafts 46 and 47 (see Fig. 2). On the shafts 46 and 47 are abutment nuts 54 and 55 adjacent the toe parts 52 and 53. On the parts of the shaft 46 between the toes 52 and the lower end portions of the arms 32, and on the parts of the shaft 47 between the toes 53 and the upper end portions of the arms 31, are rollers 56 and 57 which rotate freely on their respective shaft portions. These rollers 56 and 57 roll or run on race plates 58 and 59 suitably attached to the bases 15 and 17. The lever arm parts 31 and 34 and the lever arm parts 32 and 35 may be fixed together by any suitable means, such as by spot welding.

To the lower end portion of the lever arm couples 32-35 are suitably fixed studs 60 and to these studs are connected hooked ends of coil springs 61, the other ends of these springs having hooked ends hooked in suitable apertures provided in the foot portions 36 of the lever arm couples 31-34. (See Figs. 1 and 2.) These springs 61 normally act to pull the lower parts of the lever arms together so as to raise the pad 14 to the position as shown in Fig. 1. To control the upper limit of movement of the pad 14 an anchor element 62, which may be in the form of a rope or chain or the like, may be used as desired. This element 62 is connected at its lower end to a hook 63 suitably fixed to the lower base 15 and at its upper end to a hook 64 suitably fixed to the upper base 17, as shown in Fig. 2.

For the purpose of cushioning and regulating the downward movement or extent of movement of the pad 14 on which a patient is treated certain cushioning members are preferably used, such as helical springs 65 and 66, there being two springs 65 at one end of the device and one spring 66 at the other end of the device. See Fig. 3. The lower ends of these springs may be suitably anchored to the lower base 15, as by way of straps 67 and 68 which loop over the lower coil ends of these springs 65 and 66 and which are suitably secured or fastened to the top of the lower base 15, as by screws or bolts 69, as shown in Figs. 2 and 3. The upper ends of the springs 65 and 66 press up against the lower face of the upper base

17 and anchor straps though not necessary may be likewise used if desired.

At times when it is desired to treat a patient without depressing the pad 14 the latter may be locked up in the position shown in Fig. 1 by the use of a strut link or post 10 pivotally connected at its lower end to a foot piece 11 by way of a suitable pivot pin 12, the foot piece having a sole 13 suitably fixed to the top of the lower base 15 at an end thereof as shown in Fig. 1. At the upper end of the post 10 is provided a laterally extending hook 14 adapted to fit about a depending stud 15 suitably fixed to an end part of the upper base 17 (see Figs. 1, 4 and 6). The hook part 14 abuts up against the under side of the upper base 17 and may be held clamped to it by a thumb nut 16 screwed on the stud 15. When it is desired to use the device to depress the pad 14, as shown in Fig. 8, the upper end of the strut 10 is unhooked by loosening the thumb nut 16.

In Fig. 8 is shown a patient in prone position on a chiropractic machine with the abdominal part 17 of the patient on the pad 14. When the doctor presses down on the patient's back 18 to give a desired effect to the back, there is also a pressure effect against the abdomen 17 as the pad 14 is moved down. This downward movement is straight down so that the reactive stress is conversely upward over the extent of the abdomen. In structures where the pad 14 is hinged about an axis proximate to the lower part of the abdomen, as about where the hips are located, the upper part of the abdomen would not receive any reactive stress and in most cases would be suspended above and spaced from the forward part of the pad. By use of a straight down movement of the pad 14 desired treatment of the upper part of the abdomen may be effectively utilized.

In operation the patient lies in a horizontal and procumbent position upon the machine with his abdomen upon the pad 14. When the doctor presses down on the patient's back, as at the portion 18, the abdomen portion 17 forces down the pad 14 as to a position shown in Fig. 8. The downward movement of the pad 14 is a right line movement so that the reactive stress against the abdomen is evenly distributed over the extent of the abdomen.

The downward movement of the pad 14 causes the lever arms 31-34 and 32-35 to consonantly pivot about the axes of the shafts 27 and 28 and the bearing units 26, against the restraining force of the springs 61. Coordinately the rollers 56 and 57 at the other ends of the lever means 55 roll or translate along the roller plates or races 58 and 59 so that the movement of the pad 14 will be a straight or straight line movement. The shoe and toe features 36-38, 37-39, 50-52, and 51-53 afford lateral staying against any side play or swing so that the straight or right line movement of the pad 14 will be constant and unvarying.

As the pad 14 moves down the counter stress of the springs 61 varies and to avoid a too rapid change in rate of downward movement of the pad 14, upright and directly acting springs 65 and 66 react against the pad 14 so as to even up the downward strain or movement of the pad 14. As for example, as the leverage of the lever means changes whereby the reactive stress of the springs 61 reduces the compressing of the helical springs 65 and 66 consonantly increases resulting in a more or less uniform straining and stressing. Conversely, the restoration of the pad 14, that is, its return or upward movement will

likewise be regular and uniform, and will not jump or rebound.

The chain 62 limits the upper position of the pad 14 so that it will be normally even with the other pads 12 and 13 of the machine.

When effecting a treatment wherein the pad 14 is not to be depressed the hooking of the post 70 in upright position, as shown in Figs. 1 and 6, will firmly hold the pad 14 even with the pads 12 and 13.

While we have herein described and upon the drawing shown an illustrative embodiment of the invention it is to be understood that the invention is not limited thereto but comprehends other constructions, arrangements of parts, details, features, and the like without departing from the spirit of the invention.

Having thus disclosed the invention,

We claim:

1. In a chiropractic device comprising supporting means for pads upon which a patient lies in a procumbent position, the combination therewith of a stationary base, a movable base carrying an abdominal pad, a pantographic type of lever arrangement connected to said bases for controlling relative movement of said bases in a right line direction, and resilient means connected to parts of said lever arrangement for offering a yieldable reactive stress against relative approach of said bases, said lever arrangement having mutually fulcrumed levers with an end of said levers pivotally connected to said bases and the other ends of said levers being movable along faces of said bases, said ends of said levers having laterally extending bracing portions for acting against said bases to give lateral support to said levers against side movement.

2. In a chiropractic device comprising supporting means for pads upon which a patient lies in a procumbent position, the combination therewith of a stationary base, a movable base carrying an abdominal pad, a pantographic type of lever arrangement connected to said bases for controlling relative movement of said bases in a right line direction, and resilient means connected to parts of said lever arrangement for offering a yieldable reactive stress against relative approach of said bases, said lever arrangement having mutually fulcrumed levers with an end of said levers connected to bearing means, said bearing means being connected to said bases, said bearing means having shafts, said ends of said levers having laterally extending bracing portions connected to said shaft to give lateral support to said levers against side movement, and the other ends of said levers being movable along faces of said bases.

3. In a chiropractic device comprising supporting means for pads upon which a patient

lies in a procumbent position the combination therewith of a stationary base, a movable base carrying an abdominal pad, a pantographic type of lever arrangement connected to said bases for controlling relative movement of said bases in a right line direction, and resilient means connected to parts of said lever arrangement for offering a yieldable reactive stress against relative approach of said bases, said lever arrangement having mutually fulcrumed levers with an end of said levers connected to bearing means, said bearing means being connected to said bases, said bearing means having shafts, said ends of said levers having laterally extending bracing portions connected to said shaft to give lateral support to said levers against side movement, and said other ends of said levers connected to bearing means, rollers connected to said later bearing means and located to roll along the faces of said bases.

4. In a chiropractic device comprising supporting means for pads upon which a patient lies in a procumbent position, the combination therewith of a stationary base, a movable base carrying an abdominal pad, a pantographic type of lever arrangement connected to said bases for controlling relative movement of said bases in a right line direction, and resilient means connected to parts of said lever arrangement for offering a yieldable reactive stress against relative approach of said bases, said lever arrangement having mutually fulcrumed levers with an end of said levers connected to bearing means, said bearing means having shafts, said ends of said levers having laterally extending bracing portions connected to said shaft to give lateral support to said levers against side movement, and said other ends of said levers connected to bearing means, rollers connected to said later bearing means and located to roll along the faces of said bases, said later bearing means having shafts, the other ends of said levers having laterally extending bracing portions connected to said later shaft to give lateral support to said levers against side movement.
